POWER HAMMER CONSTRUCTION

Edward A. Smith, Chatham, N. J., assignor to
 Raymond Concrete Pile Company, New York,
 N. Y., a corporation of New Jersey

Application June 26, 1951, Serial No. 233,620

15 Claims. (Cl. 61—76)

1

This invention relates to power hammers particularly adapted, among other possibilities, for use in the installation of piles and the like. The invention will be explained in connection with a form of hammer adapted for driving hollow metal cores such as are placed inside of metal pile shells for driving the latter into place, but it will be understood that various features of the invention are adapted for other possible uses.

In preparing to drive metal pile shells, it is the general practice to suspend a hollow core from the boom of a crane, in a vertical position above the desired location of the pile, a steam hammer with its ram also being suspended above the core in position to drive the core into the earth while its lower end is surrounded by succeeding sections of the pile shell. When the vertical dimension of the conventional type of steam hammer is added to the height of the usual pile core, it will be apparent that to secure the necessary "head room" for the assembly, it becomes necessary to use a crane with a very long boom and the whole assembly becomes very cumbersome and inconvenient to handle.

Heretofore in some instances efforts have been made to provide a more convenient assembly requiring less head room by using a single piston hammer and ram of a size to fit within the upper end of the core. However, such an arrangement has two serious disadvantages, first, because of the necessity of using a steam cylinder small enough to be received within the limited diameter of the core, the power of the hammer and the consequent maximum possible weight of the ram are unduly limited, and secondly, such single piston hammers can deliver only a limited number of blows per minute as compared with the double piston differential types of hammers often used for rapid pile driving. For these reasons the assembly of a single acting hammer within a core permits only comparatively slow pile driving, with the result that such an arrangement is ordinarily useful only on small jobs where the saving in cost of moving the equipment to and from the job is more important than the cost of the actual pile driving.

The present invention avoids these difficulties and involves novel arrangements permitting powerful rapidly operating double acting types of hammers and differential types of hammers to be constructed and adapted to be arranged in assembly with the upper end of a pile core with the entire ram as well as the greater part of the remainder of the hammer mounted within the upper end of the core, thus minimizing the re-

2

quired head room for the core and hammer assembly, yet permitting full advantage to be taken of the use of double acting or differential types of hammers.

- 5 The operation as well as the shape of such double acting and differential types of hammers as heretofore constructed are such that for several reasons hereinafter brought out, they could not in practice be mounted to operate within the 10 conventional type of pile core. More specifically, the present invention relates to various features making possible for the first time the assembly and operation of these general types of hammers within the upper end of a core or the like.
- 15 Further objects, features and advantages of the invention hereof will appear from the detailed description given below, taken in connection with the accompanying drawings which form a part of this specification and illustrate by way 20 of example, preferred embodiments of the invention.

In the drawings:

Fig. 1 is an elevational view, partly in section, showing the upper end portions of a pile core with 25 a double piston steam hammer assembled therewith in accordance with the invention;

Fig. 2 is an elevational view of one of the pile cores alone and showing an upper end portion thereon constructed in accordance with the 30 present invention;

Fig. 3 is an elevational view of a typical metal pile shell which is to be driven by the assembly of Fig. 1 when positioned therewith;

Fig. 4 is an enlarged vertical sectional view of 35 the upper portion of the apparatus shown in Fig. 1;

Fig. 5 is a side elevational view of the upper portion of Fig. 4 showing certain valve operating mechanism in further detail;

Fig. 6 is a sectional view taken substantially 40 along line 6—6 of Fig. 4;

Fig. 7 is a sectional view partly broken away, taken substantially along line 7—7 of Fig. 4;

Fig. 8 is a vertical sectional view taken substantially along line 8—8 of Fig. 4; and

Fig. 9 is a vertical sectional view corresponding to Fig. 4, but showing an alternative embodiment of the invention.

Referring to the drawings in further detail and 50 more particularly to the core as shown in Fig. 2, it is first noted that this core may be of a well known construction, except that the upper section 45 thereof is formed on its upper end with a portion 46 of enlarged diameter. The upper 55 rim of this latter portion is surrounded by a re-

inforcing ring or the like 17 welded thereon and having at oppositely spaced positions two pairs of lugs or the like 18, 18' between which lifting links are received as hereinafter described. With the embodiment of the invention shown in Fig. 9 and as hereinafter described, the upper end of the core does not need to be formed with a portion of enlarged diameter.

Referring now particularly to Figs. 1 and 4, the hammer assembly as shown comprises a body member 20 which includes an upper cylinder 21 of relatively large diameter and a lower cylinder portion 22 of smaller diameter, these cylinder portions respectively containing pistons 21' and 22' of corresponding sizes. These pistons are integral with or rigidly mounted upon a single piston rod 23 having a lower portion 23a terminating in a tapered end 23b fitted within a corresponding cavity in the upper end of a ram 24 (Fig. 1). This tapered end is locked in position within the ram by a transverse pin as indicated at 25.

It will be noted that the lower and smaller cylinder portion of the hammer as well as the ram are received within the working portion of the core 15 which is of normal diameter, whereas the lower part at least of the larger cylinder portion of the hammer is received in the enlarged portion 16 of the core. As will be noted from the upper portions of Figs. 2 and 3, this enlarged portion is intended in use to be located above the upper end of the pile shell, that is, above the normal working parts of the core.

The lower end of the smaller cylinder portion 22 of the hammer (Fig. 4) is closed off by an annular member 26 which is secured and sealed in place as by the use of a plurality of bolts 27. The piston rod portion 23a reciprocates within the central aperture and this member 26. A ram guide cylinder 28 is secured as by welding about the lower rim of the member 26 and serves as a cylinder through the lower end of which the ram reciprocates when actuated. This ram guide cylinder also serves in conjunction with the body member 20 to enclose and retain together the hammer and ram assembly when same is withdrawn from the core.

At a position just above the ram 24, a thick rubber bumper 30 encircles the piston rod portion 23a. This bumper may be in the form of a split ring of flexible rubber which may be put into place, or readily removed for replacement when desired, through a hand hole 31 formed in the side wall of the ram guide cylinder (Fig. 1). The purpose of this bumper is to cushion the upper end of the ram with respect to the lower surface of the member 26 when the hammer is being used in such a way as to drive (i. e. to pull) the core up out of the pile shell, if the core, after driving the shell, should become jammed as it sometimes does against easy upward removal by the crane.

As shown in Fig. 1, the ram 24 is at its position of impact and for reasons hereinafter explained, the impact is preferably applied against a cap block assembly 32 of the type disclosed in U. S. patent to Kinneman No. 2,184,745. This type of cap block comprises upper and lower rigid members as at 33, 33' between which are located a stack of so-called "Belleville" washers or the like 34 to provide an assembly which will cushion the impact to a predetermined degree which does not vary materially even after receiving a large number of impacts. The lower end of this cap block rests upon an anvil block 35 forming a part

5

of the core structure. For the purposes of the particular hammer assembly herein described, an important characteristic of this type of cap block is that neither its normal vertical dimension before impact, nor its compressed vertical dimension upon impact vary materially even after a large number of impacts. For reasons hereinafter further explained, this greatly facilitates the proper actuation and timing of the valves of the double piston type of hammer herein disclosed, whereas if for example a wooden cap block were used which would become more and more compressed after repeated blows, then the position of impact of the ram with respect to the core would change upon successive impacts so as to require readjustment of the valves which control the timing of the impact.

As indicated in the lower portion of Fig. 4, if found desirable, the member 26 on its upper surface may be formed or provided with a drip retaining ring 36 to catch condensate from steam in higher parts of the hammer. This condensate may be drawn away by removing a side plug 37 when necessary and while the hammer is out of the core.

The steam passage and valve arrangements for controlling the operation of the hammer pistons will now be described. As in the case of double piston differential hammers heretofore used, the arrangement of the valves is such that the steam supply is constantly connected to the space between the pistons 21', 22', whereas pressure is supplied to the space above the large upper piston only during the greater part of the down stroke and momentarily during the final part of the upstroke to cushion the final upward movement. That is, just before the moment of impact, the steam pressure in the space above the upper piston is released and a passage from this space remains open to exhaust until the upstroke is nearly completed, whereupon pressure is again admitted above the piston 21' to cushion and stop the upstroke. Admission of the fluid pressure above the upper piston thereafter is continued and acts with the aid of gravity to force the piston assembly down again, the active and effective piston area then being equivalent to the area of piston 22'. (That part of the area of piston 21' which is in excess of the area of piston 22' will have the same pressure thereon both above and below and thus will be ineffective in contributing force to the downstroke; and that part of the area of the piston 21' corresponding to the area of piston 22' will be subject to pressure on the upper side and this will be effective together with gravity in causing the downstroke, since the underside of piston 22' is not under pressure.)

The main control valve may preferably be of the Corliss type mounted on the top of the hammer within an extension portion 29a of the body of the hammer. As shown in Fig. 8, this valve may comprise a cylindrical member 38 formed on its side with a passage 39 adapted either to connect a steam inlet passage 40 with a passage 41 entering the larger cylinder or for connecting the passage 41 with an exhaust passage 42. As shown in Figs. 4 and 5, a cam or lever member 43, is adjustably secured to one end of the valve member 38, this lever member being adapted to be operated by a reciprocating rod 44 which passes through a suitable stuffing box down into the larger cylinder space 21. During the greater part of the upstroke, the valve member 38 will be in a position so that its passage 39, as indicated by dotted lines in Fig. 8, will connect the passage

41 to the exhaust 42. Then as the piston engages the lower end of the rod 44, the valve member will be rotated counterclockwise to the position shown in full lines in Fig. 8, thus moving passage 39 to a position for connecting the source of pressure 40 to the passage 41 into the cylinder.

Pressure is maintained in the space between the two pistons by a branch passage 46 (Fig. 6) connecting the source of pressure supply to a vertical passage 46a which runs down through the large cylinder wall to a discharge port 46b.

For turning the valve member 38 in the clockwise direction (as viewed in Fig. 8) another passage 47 runs from a port 47a opening into the lower part of the smaller cylinder, this passage 15 extending up through the cylinder walls as at 47b and continuing as indicated at 47c (Fig. 6) into the end of a valve control cylinder 48. This cylinder contains a piston 49 having a piston rod extending out for engagement with a lever 50 attached adjustably to a shaft 51 protruding from the end of the valve member 38. The piston rod for the piston 49 may protrude out through a suitable housing 52 and when, during the downstroke of the hammer, the lower piston 22 passes the port 47a, then the pressure existing in the space between the two hammer pistons will be communicated through the passage 47 up into the valve control cylinder 48, thus acting to move the lever 50 in a direction to shift the valve member 38 to the dotted line position indicated in Fig. 8 (i. e. to connect the exhaust passage 42 to the passage 41, thus releasing the pressure above the large piston 21'). Since the valve is located very close to the top of the large cylinder, the pressure in this cylinder will be exhausted very rapidly just before the moment of impact, and thus it is unnecessary to cut off such pressure until the full stroke is almost completed.

The main casting or body of the hammer may be lifted by a crane attached to an eyelet 54 and by this means the hammer may be dropped into place within or lifted out of the core. The upper portion of the larger cylinder of the hammer is formed externally with an enlarged portion 55 adapted to rest upon a stack of annular shock absorbing members 56 formed of rubber laminated with other suitable sheet material as desired, these shock absorbent members in turn resting upon the top edge of the core assembly. The cushioning means 56 acts to cushion the jar when the hammer drops on the core again just after the core has been driven ahead by a blow of the hammer.

When the hammer is to be lifted out of place 55 after driving the pile shell, then in order simultaneously to lift out the core assembly, a pair of lifting links 57, 57' are suitably connected pivotally to the upper portion of the hammer as shown, these links being of inverted T-shape and the lower ends thereof being received within the pairs of lugs 18, 18' and removably held there in place as by pins 58, 58'.

It will be noted that when the hammer is acting on the downstroke, the pressure within the larger cylinder will not only act downwardly but react upwardly against the top cylinder head and thus unless the cylinder assembly is undesirably heavy or the steam pressure is kept undesirably low, the arrangement as thus far described would cause the cylinder assembly to be forced upwardly during each down stroke. Since it is highly desirable to keep the weight of the cylinder assembly as light as possible to permit a heavy ram to be lifted along therewith without 75

using an excessively large crane, means are provided according to the invention temporarily and automatically to cause the cylinder assembly to grip the core during the period while the pistons are being forced down by steam pressure above the upper piston. Such gripping action, however, is preferably automatically released just before the impact so that the core being driven will be free to move downwardly under the impact without transmitting the force of the impact to the suspended hammer cylinder assembly and without retarding the downward movement of the core by reason of such gripping action.

In the preferred form, such temporary gripping means comprises a plurality of pistons as at 60, 60' located in cylinders as at 61, 61', the axes of which extend radially from the main axis of the hammer. While only two of these cylinder and piston elements are indicated in Fig. 4, it will be understood that several more, if desired or necessary, may be arranged at various angles about the axis of the hammer within the housing 20, as indicated in Fig. 7. These pistons, when their corresponding cylinders are subjected to pressure, will be moved outwardly into firm frictional engagement with the interior walls of the enlarged portion 16 and the core. Since these pistons are to be active only when the upper surface of the large piston 21' is subjected to pressure, it will be apparent that pressure may be supplied to the cylinders as at 61, 61' through a passage such as at 63 extending from a port 64 in the top of the large cylinder, such passage 63 extending down to an annular passage 65 (Fig. 7) connected to all of the cylinders such as at 61, 61'. The almost instantaneous drop in pressure in the space above the large piston at the moment just prior to impact, results in a corresponding immediate drop in the pressure in back of the pistons 60, 60', thus immediately releasing their gripping action on the core and permitting the core to be driven ahead without any opposition from the gripping action.

As above noted, the hammer according to this invention is so constructed that it may be used to strike an upward blow for dislodging the core to permit its removal after driving a pile shell, even though the core may be so jammed in respect to the shell that it is impossible to remove it with the lifting force of the crane alone. For this purpose valve means is provided for somewhat restricting the admission of cushioning pressure above piston 21' as it approaches the top of its stroke and so that the cushioning effect is reduced just enough whereby the rubber bumper 30 located on top of the ram will engage the member 26 (Fig. 4) with a blow having the desired force for lifting the core. When the core is to be pulled, the engineer first applies an upward pull to the eyelet 54 by the use of block and tackle, thus bringing the T-heads of the links 57, 57' up against the undersides of the lugs on the core. If this does not pull the core, he then operates the hammer in such a manner as to strike an upward blow. This blow is delivered to the core through the links. The valve means for restricting the cushioning effect as the hammer approaches the top of the stroke, may take the form for example of a butterfly valve 67, suitably mounted pivotally within the pressure intake passage 40 at a point between the main valve member 38 and the branch passage 46 (Figs. 5 and 6). This butterfly valve may be manually controlled by a suitable lever 68, which lever may be fixed in either of two positions by a retractable

pin 69 or by other suitable means. Normally this butterfly valve is positioned as indicated by full lines in Fig. 6 so as to offer no substantial restriction to the passage of steam into and through the valve member 38 to the large cylinder. However, when it is desired to have the hammer impart an upward impact, then the butterfly valve is moved to the angle indicated by dotted lines in Fig. 6, thereby somewhat restricting the admission of pressure. This will not only reduce the cushioning effect at the end of the upstroke to a sufficient degree to permit the bumper 30 to strike an upward blow against the hammer assembly, but also, during the subsequent downstroke of the hammer, the admission of fluid pressure will be so restricted that the hammer will not impart strong downward impacts.

As above noted, the cap block 32 against which the ram impact is imparted (lower part of Fig. 1) should be of a type which does not progressively change its normal vertical dimensions as the result of repeated impacts. The advantage of a cap block of this type will now be apparent after considering the above description of the control valve and steam passage arrangements. That is, assuming that a cap block were used of a type such, for example, as of wood, which would become pounded successively to smaller and smaller vertical dimensions, then the location with respect to the core at which the impact takes place will move downward somewhat with each succeeding blow. Consequently either the timing of the cut off of the pressure above the larger piston would have to be changed, or else the maximum possible period of maintenance of such pressure for most effective action of the hammer will be decreased. Any step-by-step shifting of the timing of the valves would, of course, involve complicated and possibly undependable mechanism. Also, if a wooden cap block is used, there will not only be a variation in the force of successive blows, but also the ram will tend to damage the remainder of the hammer assembly because of over-stroking unless the wooden block is changed at inconveniently frequent intervals. It may further be noted that if the ram were to impart its impact directly to the anvil block or directly to any other solid member, then no cushioning effect would be provided and severe destructive shocks would be imparted to the piston and ram assembly and other parts. But with the type of cap block above disclosed, all such difficulties are readily avoided.

With all of the embodiments of the invention it will be apparent that an assembly is provided such as to permit the powerful rapid-blow type of double piston differential hammer to be used, and yet used in such a way that only a small part of the height of the hammer and ram assembly protrudes above the core. And by placing the upper larger cylinder of this type of hammer above the working part of the core, this cylinder can readily be made as large as desired and hence in practice there is no definite limit to the weight of the ram which can be used. (The lifting power of the hammer depends upon the pressure against the area of the underside of the large piston minus the area of the small piston.) The weight of the ram may be greatly increased if desired by increasing its length, and yet a hammer with an upper piston sufficiently large to lift such a heavy ram can still be provided and largely contained in the core, since the large cylinder part only of the hammer need be located above the working part of the core where the diameter is

5 limited by the diameter of the pile shell. It, therefore, becomes possible with this invention to use a ram as heavy as desired within reasonable limits and also to increase greatly the number of blows per minute as compared with prior assemblies of single piston hammers within pile cores.

10 As above stated, with the embodiment of the invention shown in Fig. 9, the core 75 does not have to be provided with an enlargement at its upper end. Instead the flange formation at 76 at the lower part of the larger cylinder portion of the hammer may rest directly upon a rubber cushion ring 77 which in turn rests upon the upper end of the core 75. And with this embodiment the pistons as indicated at 78, 78' for temporarily gripping the core, are located in the lower end portion of the smaller cylindrical part 15 of the hammer, the fluid pressure passage for controlling these pistons being indicated at 79 extending from an intake port 80 within the upper end of the larger cylinder down to an annular passage 81 at the region of the piston 78, 78'. The construction and operation of other parts of the embodiment of Fig. 9 will be apparent from the above description of Fig. 4.

20 It may be noted that temporary gripping means in the form of pistons such as at 60, 60' of Fig. 4 and 78, 78' of Fig. 9 may be used for various types 25 of hammers other than the differential types here disclosed, but which are double acting and which may consequently tend to rise in a core or casing during a part of the cycle of operation, in the absence of such gripping means.

30 Although certain particular embodiments of the invention are herein disclosed for purposes of explanation, various further modifications thereof, after study of this specification, will be apparent to those skilled in the art to which the invention pertains. Reference should accordingly be had to the appended claims in determining the scope of the invention.

35 What is claimed and desired to be secured by Letters Patent is:

40 1. The combination comprising: a tubular pile core; a double piston differential type of fluid pressure hammer located in said core; a ram in said core beneath said hammer and connected to the piston rod thereof, the lower and smaller piston of the hammer being contained in a cylinder portion of external dimensions such that same is 45 slidable within the normal working portion of the core, and the upper and larger piston of the hammer being contained in a cylinder portion larger than, and above the normal working portion of the core.

50 2. The combination comprising: a tubular pile core; a double piston differential type of fluid pressure hammer located in said core; and a ram in said core beneath said hammer and connected to the piston rod thereof, the lower and smaller piston of the hammer being contained in a cylinder portion of external dimensions such that same is 55 slidable within the normal working portion of the core, and the upper and larger piston of the hammer being contained in a cylinder portion of larger diameter than, and above the normal working portion of the core, said hammer having control valve means for the pistons thereof located upon the upper end of the larger cylinder portion.

60 3. A double piston differential type of fluid pressure hammer and ram assembly adapted for telescopic assembly with tubular pile cores and the like, comprising in combination: relatively

large and smaller adjoining cylinder portions containing pistons respectively of corresponding sizes and secured to a common piston rod, the smaller cylinder portion being lowermost and having a tubular ram guide attached to and depending from the lower end thereof; and an elongated ram in said guide secured at its upper end to said piston, said smaller cylinder portion and said ram guide being adapted to be slidably received within the working part of a pile core.

4. The combination comprising: a tubular pile core having an upper end portion of enlarged diameter as compared with the diameter of the normal working portion of the core; a double piston differential type of fluid pressure hammer located in said core; and a ram in said core beneath said hammer and connected to the piston rod thereof, the lower and smaller piston of the hammer being contained in a cylinder portion of external dimensions such that same is slideable within the normal working portion of the core, and the upper and larger piston of the hammer being contained in a larger cylinder portion of external dimensions such that same is at least partially slideable within the enlarged core portion but not into said working portion of the core.

5. A fluid pressure operated hammer adapted for telescopic assembly with a surrounding casing or the like, said hammer having fluid pressure operated means in its side walls for frictionally gripping the interior walls of the casing or the like to prevent movement of the hammer with respect to the latter.

6. A fluid pressure operated hammer adapted for telescopic assembly with a surrounding casing or the like, said hammer having fluid pressure operated piston means in its side wall, movable transversely of the main axis of the hammer to frictionally grip the interior wall of the casing or the like, and conduit means extending from said piston means to the same source of fluid pressure as provided to operate the hammer.

7. A double acting fluid pressure operated hammer adapted to be received in a casing or the like, said hammer having fluid pressure operated means thereon for gripping the interior wall of the casing, and connections for bringing the fluid pressure which operates the hammer during a predetermined part of its stroke into communication with said fluid pressure operated means to cause the latter to grip the casing during said part of the stroke.

8. A double acting fluid pressure operated hammer adapted to be received in a casing or the like to be driven by the hammer, said hammer having fluid pressure operated means thereon movable transversely of the axis of the casing for frictionally gripping the interior wall of the casing, and connections for bringing the fluid pressure which operates the hammer into communication with said fluid pressure operating means, said connections including means automatically to release pressure from said fluid pressure operating means at a time close to the moment of impact of the hammer, thereby releasing the gripping action on the casing to permit the casing to be freely driven by the impact.

9. A double piston differential type of fluid pressure operated hammer adapted for telescopic assembly with a surrounding casing or the like, said hammer having fluid pressure operated means in its side wall for frictionally gripping the interior wall of the casing or the like, and conduit means for bringing said fluid pressure operated means into communication with and under the

control of the same fluid pressure as provided in the larger cylinder of the differential hammer.

10. In combination: a fluid pressure operated hammer of a type having a piston and adapted to strike a downward blow by the action of fluid pressure above such piston and having an automatically controlled valve for releasing such pressure at a time close to the moment of impact; a casing within which such hammer is received, said hammer having fluid pressure means thereon for gripping the interior of the casing; and connections for bringing said fluid pressure operating means into communication with, and for operation by, said fluid pressure above the piston, to thereby cause said means to grip the casing during the downstroke of the hammer until release of such pressure.

11. The combination comprising: a tubular pile core; and a double piston differential type of fluid pressure hammer, the lower and smaller piston of the hammer being contained in a cylinder portion slidably received within the core, the upper and larger piston of the hammer being contained in a cylinder portion larger than and at least partially located above the normal working portion of the core.

12. The combination comprising: a tubular pile core; a double piston differential type of fluid pressure hammer, the lower and smaller piston of the hammer being contained in a cylinder portion slidably received within the core, the upper and larger piston for the hammer being contained in a cylinder portion too large to be received in the core; and a cushioning means interposed between the upper end of the core and peripheral parts of the latter cylinder portion.

13. In combination: a fluid pressure operated hammer of a type having a piston and piston rod and adapted to strike a downward blow by the action of fluid pressure above such piston and having an automatically controlled valve for releasing such pressure at a predetermined time close to the moment of impact; a ram connected to the lower end of said piston rod; and a cap block beneath such ram adapted to impart blows from the ram to an anvil block, said hammer, ram and cap block being adapted to be received in a tubular casing connected to the anvil block to be driven thereby, said cap block comprising a plurality of superposed members, which are resilient to a predetermined limited degree in the direction of the axis of the ram, and which serve to maintain the cap block normally with a substantially constant vertical dimension prior to each impact.

14. In combination with a tubular pile core: a double piston differential type of fluid pressure hammer at least partially received in such core and connected to the upper end thereof by linkage means, said hammer having automatically controlled valve means and connections for maintaining substantially constant pressure between the pistons and for maintaining pressure above the larger piston during the greater part of the downstroke, and the final part of the upstroke for cushioning purposes; a piston rod connected to the hammer pistons and extending downwardly therefrom; a ram connected to the lower end of said piston rod; a bumper interposed between said ram and the lower part of the body of the hammer; and valve means for limiting the admission of pressure fluid above the larger piston, thereby to limit the cushioning of the upstroke whereby the

11

hammer will strike an upward blow for imparting an upward blow through such linkage means to the core.

15. A double piston differential type of fluid pressure operated hammer having interconnected upper and lower pistons, contained respectively in relatively large and smaller cylinders, and valve means and connections for maintaining substantially a constant pressure between said pistons and for maintaining pressure above the larger piston during the greater part of its downstroke and the final part of its upstroke for cushioning purposes, said valve means

5

10

12

including a push rod extending into the upper cylinder and positioned to be actuated by the larger piston as it approaches the limit of its upstroke to then actuate the valve means to admit pressure above the larger piston, and a fluid pressure operated means connected to receive operating fluid pressure from the space between the pistons at a time near the end of the downstroke for restoring said valve means to closed position.
